REAR SIGHT FOR FIREARMS

Harold F. Mossberg, New Haven, Conn., assignor
to O. F. Mossberg & Sons, Inc., New Haven,
Conn., a corporation of Connecticut

Application June 9, 1943, Serial No. 490,389

9 Claims. (Cl. 33—56)

1

This invention relates to improvements in sights for firearms and more particularly to an adjustable rear sight having improved elevation and windage adjusting means in its structure.

One object of this invention is to provide in a rear sight for firearms very efficient elevation and windage adjusting means of improved form and which is comprised of a minimum number of components.

Another object of this invention is to provide a rear sight for a firearm of the above nature having a sight leaf adapted to be elevated at one end and means at its other end adapted to adjust the elevated end laterally.

A further object of this invention is to provide in a rear sight of the above nature, a sight base, and a sight leaf which is so resiliently connected to the base as to be substantially floating in respect thereto.

A still further object of this invention is to provide an improved rear sight for firearms which will be relatively inexpensive to manufacture, simple in construction, of relatively few components, compact, ornamental in appearance, and very efficient and durable in use.

With the above and other objects in view, which will appear as the description proceeds, there have been illustrated in the accompanying drawing two forms in which the invention may be embodied in practice.

In the drawing:

Figure 1 is a side elevational view of a rear sight embodying the features and principles of this invention;

Figure 2 is a rear view of the sight shown in Figure 1;

Figure 3 is a top plan view of the same;

Figure 4 is a cross-sectional view taken on the line 4—4 of Figure 3;

Figure 5 is a cross-sectional view taken on the line 5—5 of Figure 3;

Figure 6 is a sectional view taken on line 6—6 of Figure 3 but with the sight leaf in an elevated position;

Figure 7 is a top plan view of the sight of this invention with the leaf in a position adjusted by the windage adjusting means; and

Figure 8 is a broken top view of a slightly modified form of a rear sight for firearms embodying the features of this invention.

Referring to the drawing wherein like reference numerals designate like parts throughout the several views, the numeral 11 denotes the sight base which has a depending dovetail member 12 whereby the sight may be detachably con-

2

nected to a part of a firearm such as a receiver 13, or the barrel thereof, as indicated in Figure 1. The base 11 is generally U-shaped in cross-section having laterally spaced apart side flanges 14 and 15 upstanding from the respective sides of the base 11.

Floatingly disposed between the side flanges 14 and 15 is a sight leaf 16 having lugs 17 and 18 extending from each side and at substantially the center thereof toward and into engagement with the side flanges 14 and 15 respectively. The outer edge 19 of each of the lugs 17 and 18 which is in engagement with the respective side flange is arcuate in shape, the radius of which is substantially one-half the dimension between the opposing surfaces of the side flanges 14 and 15 whereby the leaf 16 may pivot laterally between these flanges about the center of the arcuate edges 19.

To maintain the sight leaf 16 in any of its laterally adjusted positions in respect to the side flanges 14 and 15 leaf springs 21 and 22 are provided. The springs 21 and 22 are identical in shape each having a widened and slotted end 23, the slot 24 thereof being adapted to receive the respective lug 17 or 18 over which this end is disposed. Each spring is bowed outwardly at a portion 25 into engagement with the adjacent side flange 14 or 15 and has its other and narrowed end 26 in engagement with the adjacent side edge of the sight leaf 16. Clearance slots 27 and 28 are formed in the base 11 to accommodate the widened ends of the springs 21 and 22.

A post 29, having a peep hole 31, is secured to, or formed as a part of, the leaf 16, and is disposed adjacent the rear end 32 of the leaf 16 and vertically extends upwardly therefrom. The rear end 32 of the leaf 16 is widened to overlap the rear end of each of the side flanges 14 and 15. The laterally extending portions 33 and 34 at the widened end of the leaf are each provided with a V-shaped front edge 35 adapted to fit into any one of a vertical series of V notches 36 formed in the rear edge of each of the flanges 14 and 15. The leaf 16 at its widened end 32 is bent downwardly and further widened to form a finger engaging member 37 by which the leaf 16 may be readily grasped to dispose the V-shaped front edges 35 in a selected V notch 36 to vary or adjust the elevation of the sight in accordance with indicia stamped, or imprinted, on the outer surface of the side flanges 14 and/or 15.

A stud 38 is rotatably secured to the front end 39 of the sight leaf 16, for instance by riveting as shown, and extends downwardly in front

of the front end of the base 11. A coiled spring 41 is disposed in a hole 42, provided in the base 11 for receiving the same, and reacts between the base 11, at the bottom of the hole 42, and the stud 38 to urge the leaf 16 forwardly to maintain the V-shaped edges 35 in the selected V notch 36. The base 11 may be cut away as at 43 to form clearance for the stud 38.

A windage screw 44 having a knurled head 45 is provided whereon the sight leaf 16 is pivoted to swing in its elevating movements and whereby it may be adjusted laterally to compensate for the direction and velocity of the wind wherever the firearm is being used. The screw 44 is screw-threaded through the stud 38 and extends beyond this stud 38 at both sides thereof in under and in rotatable engagement with the under-surface of forwardly extending lugs 46 and 47, which lugs are formed integral with, and extend from, the side flanges 14 and 15 respectively. The surface 48 of the screw head 45 is provided with a plurality of equally spaced apart notches 49 in which a steel ball 51 is adapted to seat to releasably lock the screw 44 against accidentally turning and to indicate the amount of adjustment being made. The ball 51 is rotatably held in a hole 52 provided in the side flange 15 by slightly spinning over the edge of the hole after the ball 51 has been inserted therein, (not shown). The notched face 48 of the screw head 45 is held firmly against the ball 51 by action of the springs 21 and 22 through the sight leaf 16 and the stud 38.

The modified form, illustrated in Figure 8, differs from the previously described form only in having the rear end portion of the leaf 61 provided as a separate part which is firmly but rotatably pivoted to the remaining front portion 62 by a pivot pin 63.

By the provision of the above described new and useful structure, an improved rear sight for firearms is provided having a sight leaf which is readily and efficiently adjusted to compensate for the distance the target is from the user, or length of the range, and to compensate for the direction and velocity of the wind. The sight of this invention is particularly simple in construction, of a minimum number of parts, and is accurate and dependable in use.

The provision of a common means, the windage screw 44, to form a pivot for the leaf 16, and an adjusting means to laterally swing the leaf, eliminates the usual use of two parts for these purposes. The provision of the lugs 17 and 18, which form bearing members for the leaf 16 in its lateral swinging movements, permits the leaf 16 to be easily swung laterally while in any of its elevated positions, and thus increases the life of the sight by obviating any binding at its pivotal point, bending, or straining, of the leaf when it is elevated, and eliminates the usual requirement of separate and additional parts.

It will be understood that the novel features and principles of this invention may be embodied in other specific forms without departing from the spirit and essential attributes thereof, and it is therefore desired that the present embodiment be considered in all respects as illustrative and not restrictive, reference being had to the claims rather than to the foregoing description to indicate the scope of the invention.

Having thus fully disclosed the invention, what is claimed as new and for which it is desired to secure Letters Patent, is:

1. In a rear sight for firearms, a base having 75 spaced apart side flanges, a sight leaf floatingly

spaced apart side flanges, a sight leaf floatingly mounted for swinging movement laterally on said base and between said flanges, said sight leaf having lugs extending from its sides and intermediate its ends into engagement with said flanges and upon which said sight leaf is pivoted, and a windage screw operably engaging one end of said leaf to laterally swing it and upon which said leaf is pivoted to swing upwardly whereby its other end may be elevated.

2. In a rear sight for firearms, a base having spaced apart side flanges, a sight leaf floatingly mounted for lateral swinging movement on said base and between said flanges, means upon which said sight leaf pivots in its lateral swinging movements on said base, a series of vertically spaced V notches provided in corresponding ends of each flange, V surfaces formed on a first end of said leaf engageable in any selected notch in said flanges, and a windage screw operably engaging the second end of said leaf to laterally swing it and upon which said leaf is pivoted to swing upwardly whereby its first end may be elevated.

3. In a rear sight for firearms, a base having spaced apart side flanges, a sight leaf floatingly mounted for swinging movement laterally on said base and between said flanges, means upon which said sight leaf pivots in its lateral swinging movements in respect to said base, a windage screw operably engaging one end of said leaf to laterally swing it and upon which said leaf is pivoted to swing upwardly whereby its other end may be elevated, a head on said screw disposed outside of one of said flanges with a face overlapping the same, a ball seated in a hole provided in the said flange, slots in the overlapping face of said screw head to selectively receive the ball, and resilient means reacting between each side of the leaf and the adjacent flange to resiliently lock the ball in the selected slot.

4. In a rear sight for firearms, a base having spaced apart side flanges, a sight leaf floatingly mounted for swinging movement laterally on said base and between said flanges, said sight leaf having lugs extending from its sides and intermediate its ends into engagement with said flanges and upon which said sight leaf is pivoted, a windage screw operably engaging one end of said leaf to laterally swing it and upon which said leaf is pivoted to swing upwardly whereby its other end may be elevated, a head on said screw disposed outside of one of said flanges with a face overlapping the same, a ball seated in a hole provided in the said flange, slots in the overlapping face of said screw head to selectively receive the ball, and resilient means reacting between each side of the leaf and the adjacent flange to resiliently lock the ball in the selected slot.

5. In a rear sight for firearms, a base having spaced apart side flanges, a sight leaf floatingly mounted for lateral swinging movement on said base and between said flanges, means upon which said sight leaf pivots in its lateral swinging movements in respect to said base, said leaf having a rear end piece pivoted thereto at a first end thereof, a series of vertically spaced V notches provided in corresponding ends of each flange, V surfaces formed on the said rear end piece engageable in any selected notch in said flanges, and a windage screw operably engaging the second end of said leaf to laterally swing it and upon which said leaf is pivoted to swing upwardly whereby said rear end piece may be elevated.

6. In a rear sight for firearms, a base having spaced apart side flanges, a sight leaf floatingly

2,407,437

5

mounted for swinging movement laterally on said base and between said flanges, said sight leaf having lugs extending from its sides into engagement with said flanges and upon which said sight leaf is pivoted, said leaf having a rear end piece pivoted thereto at a first end thereof, a series of vertically spaced V notches provided in corresponding ends of each flange, V surfaces formed on the said rear end piece engageable in any selected notch in said flanges to elevate said rear end piece, and a windage screw operably engaging the second end of said leaf to laterally swing it and upon which said leaf is pivoted to swing upwardly whereby said rear end piece may be elevated.

7. In a rear sight for firearms, a base having spaced apart side flanges, a sight leaf disposed between said side flanges, means to pivot a first end of said leaf to said base for upward swinging movement to elevate the other end of the leaf and upon which said first end of the leaf is transversely movable, and a lug extending from each side of said leaf into engagement with the adjacent side flange, the flange engaging end of each lug being arcuate in shape to permit lateral swinging of said leaf.

6

8. In a rear sight for firearms, a base having spaced apart side flanges, a sight leaf disposed between said flanges, a windage screw upon which a first end of said leaf is pivoted for upward swinging movement to elevate the other end thereof and by which said first end of the leaf is swung laterally, and a lug extending from each side of said leaf intermediate its ends into engagement with the adjacent side flange, the flange engaging end of each lug being arcuate in shape to provide a pivotal bearing upon which said leaf may laterally swing.

9. In a rear sight for firearms, a base having spaced apart side flanges, a sight leaf disposed between said side flanges, a lug extending from each side of said leaf intermediate its ends into engagement with the adjacent side flange, the flange engaging end of each lug being arcuate in shape about a common center to provide a pivotal bearing upon which said leaf may laterally swing, and common means upon which an end of said leaf is pivoted to said base, for upward swinging movement to permit elevation of the other end of said leaf, and to laterally swing said leaf upon operation of said common means.

HAROLD F. MOSSBERG.
